UNITED STATES PATENT OFFICE.

LOUIS H. SCHEIDEMANTEL, OF WINONA, MINNESOTA, ASSIGNOR OF ONE-HALF TO
WILLIAM B. SCHEIDEMANTEL, OF WINONA, MINNESOTA.

OIL-BURNER.

1,174,902.

Specification of Letters Patent.

Patented Mar. 7, 1916.

Application filed February 25, 1915. Serial No. 10,527.

To all whom it may concern:

Be it known that I, LOUIS H. SCHEIDEMANTEL, a citizen of the United States, residing at Winona, in the county of Winona 5 and State of Minnesota, have invented certain new and useful Improvements in Oil-Burners, of which the following is a specification.

The invention provides a burner designed 10 most especially for utilizing oil, such as kerosene or distillate as fuel, the burner being of such formation as to insure a practically perfect combustion, thereby preventing the giving off of free carbon and the deposit of soot upon parts of the stove or other structure with which the burner is associated.

A further purpose of the invention is the provision of a burner of the character hereinbefore stated which may be readily installed in the fire box of a cook stove or range, or in the fire pot of a heater or like structure, said burner being readily adjustable to admit of the direction of the flame 25 being adjusted to meet varying conditions which may arise in the installation or use of the burner.

A further purpose of the invention is the provision of a burner which may be quickly 30 and economically constructed without requiring special castings or fittings, such burner being simple in the arrangement of its parts and effective in operation and which will utilize oil and prevent the formation of residue which would ordinarily render a 35 burner of this type unfitted for further effective service without requiring the parts to be dismembered and cleaned.

With these and other objects in view, 40 which will readily appear as the nature of the invention is better understood, the same consists in the improved construction and novel arrangement and combination of parts which will be hereinafter fully described 45 and particularly claimed.

In the accompanying drawings has been 50 illustrated a simple and preferred form of the invention, it being, however, understood that no limitation is necessarily made to the precise structural details therein exhibited, but that changes, alterations and modifications within the scope of the invention as claimed may be resorted to when desired.

Referring to the drawings,—Figure 1 is

a perspective view of a burner embodying 55 the invention showing the same applied to a cook stove or range; Fig. 2 is a transverse section of the burner and stove; Fig. 3 is a front view of the burner; Fig. 4 is a perspective view of the burner.

Corresponding and like parts are referred to in the following description and indicated in all the views of the drawings, by the same reference characters.

The burner comprises a plurality of 65 burner members A, B and C, the members A and B being of similar or like formation and the member C comprising a number of burner elements D and E of similar or like structure. The burner members A and B 70 are chiefly intended for the fire box of a cook stove or range or the fire pot of a heater or like structure. The burner member C, including the elements D and E, is designed most especially for the oven of 75 a cook stove or range, as indicated most clearly in Figs. 1 and 2 of the accompanying drawings. A supply pipe a is connected with the burner member A and directs the fuel thereto. A supply pipe b has connection 80 with the burner member B and serves to lead the fuel thereto. A supply pipe c is provided for furnishing the fuel to the burner member C. Each of the supply pipes is provided with a needle valve for controlling the flow of the fuel. The needle 85 valves are indicated at 1, 2 and 3 and are associated with the respective supply pipes a, b and c. A header 4 has the several pipes 90 a, b and c connected thereto, the connections including the several needle valves. A pipe 5 connects with the header 4 and leads to the supply of fuel which may consist of a tank or other form of container, not shown, suitably disposed at a convenient and safe 95 point. It is to be understood that the several needle valves, the header 4 and the connections between such header and needle valves are located exterior to the stove or like structure.

Inasmuch as the burner members A and B are of similar or like formation a detailed description of one will suffice for a clear understanding thereof. Each of the burner members A and B comprises a horizontal 105 tube 6, vertical members 7 and 8 depending from opposite ends of the tube 6, a lower horizontal member 9 and a burner tip 10.

Longitudinal tubes 11 and 12 are disposed upon opposite sides of the vertical members or tubes 7 and 8 and are connected at one end by means of a transverse tube 13 and 5 elbows 14. A vertical tube 15 is connected with the opposite or inner end of the longitudinal tube 11 by means of elbows 16 and 17, such elbows having a right angular arrangement. The elbows 16 are of the type 10 known in the trade as street L's. The tip 10 is connected to the tube 9 by means of a street L 18. Elbows 19 and 20 connect the vertical tube 7 with the longitudinal tube 12. The elements 19 are street L's. The tubes 6, 15 7 and 8 are connected by means of ordinary elbows 21. The tubes 8 and 9 are connected by elbows 22. An elbow 23 connects the vertical tube 15 of the burner member B with the supply pipe b. The tube 15 of the 20 burner member A is connected with the supply pipe a by means of elbows 24 and 25 and a nipple 26. The burner tip 10 is disposed centrally beneath the horizontal tube 6 and the latter is arranged in the zone of 25 the heat or flame from the burner tip, thereby admitting of the conversion of the liquid fuel thereto into vapor. A deflector 27 is disposed above the burner tip 10 and is attached to the horizontal tube 6. The deflector 27 may be of any construction and its 30 purpose is to spread the flame thereby bringing the several tubes of the burner member within the heating zone of the flame so as to supplement the action of the tube 6 in generating gas or converting the liquid fuel into vapor to be burned at the outlet of the tip 10. The several elements are connected by screw thread joints and as a result the parts 35 may be readily assembled and the burner as a whole adapted to the stove, heater or like structure to which it is to be fitted. The street L 18 admits of inclining the burner tip 10 to the right or to the left so as to direct the flame in the required direction. The 40 street L 19 admits of inclining the tube 6 to the horizontal with the result that the burner tip 10 may be inclined in a direction at a right angle to the adjustment resulting from turning the street L 18 about the tube 45 9. The street L 16 admits of leveling the burner member.

The burner member C comprises a T fitting 28, nipples 29, street L's 30, T fittings 31, street L's 32 at opposite ends of the fittings 50 31 and burner tips 33, the latter being connected to the street L's by means of nipples 34. The burner member C is connected to the supply pipe c by means of a nipple 35, a street L 36 and an elbow 37. The street 55 L 36 admits of the burner member C being leveled and such burner member may be raised or lowered by turning the elbow 37 about the supply pipe c. The burner elements D and E are of substantially U-shape, 60 each comprising the fittings 31, 32, 33 and 65

34. The street L's 32 may be turned in the T fittings 31 so as to incline the burner tips 33 to give proper direction to the flame.

As indicated most clearly in Figs. 1 and 2, a cook stove or range having a burner constructed in accordance with the invention installed therein has the burner members A and B disposed within the fire-box and the burner members D and E arranged in the space formed between the top of the 70 stove and the top of the oven so as to direct the flame into such space in a manner to insure its positive circulation around the oven. A drip pan 38 is associated with each of the burner members A and B and 75 is preferably suspended from the element 9 and is adapted to receive the fuel escaping from the outlet after the needle valve has been opened. When starting the burner 80 the needle valve 1 or 2 is opened according to which one of the burner members A or B is to be lighted. If both burner members are to be lighted both of the needle valves 1 and 2 are to be opened. The oil 85 escaping from the burner tips 10 drips into the pan, or pans 38, and is ignited and after burning for a short time heats the elements of the burner members to such an extent as to vaporize the oil passing therethrough, 90 such vapor escaping at the outlets of the burner tips 10. The heat from the burner members A and B is sufficient to heat the burner elements D and E so that such burner elements may be quickly brought 95 into service when required it not being necessary to prime such burner elements as is necessary when starting the burner members A and B. When the needle valve 3 is opened the fuel passes to both burner elements D and E. The burner members A and 100 B may be independently controlled since each has a separate controlling valve.

It is to be understood from the foregoing taken in connection with the accompanying drawings that the burner is of such construction as to admit of the several burner members being independently adjusted to give proper direction to the flame and that the burner may be readily installed and adapted to varying conditions and location 115 since the several tubular elements may be readily substituted by other tubular elements or nipples of different length.

Having thus described the invention, what is claimed as new is:—

1. An oil burner comprising upper and lower horizontal tubes, a vertical tube connecting the horizontal tubes at one end, a burner tip connected with the free end of the lower horizontal tube and disposed in 125 vertical line with the upper horizontal tube, longitudinal tubes arranged upon opposite sides of a plane passing vertically through the upper and lower horizontal tubes and connected at one end and disposed in a 130

plane mid-way between the said upper and lower horizontal tubes, a connection between the upper horizontal tube and one of the longitudinal tubes and a fuel supply pipe connected with the other longitudinal tube.

2. A burner comprising a tube, street L's at the ends of the tube, T-fittings connected to the street L's, other street L's fitted to the ends of the T-fittings, and burner tips fitted to the street L's.

3. A burner comprising a header, valved pipes connected with the header, two similar burner members having connection with two of the valved pipes and adapted to be tilted longitudinally and laterally, each of said burner members comprising upper, lower and longitudinal tubes, the latter be-

ing disposed midway between and upon opposite sides of the upper and lower tubes and connected at their outer ends, a vertical tube connecting the upper and lower tubes, a burner tip at the inner end of the lower tube, the inner ends of the longitudinal tubes being connected respectively to a valved pipe and the inner end of the upper tube, a longitudinal tube connected to the third valved pipe, and burners at the ends of the last mentioned tube.

In testimony whereof I affix my signature in presence of two witnesses.

LOUIS H. SCHEIDEMANTEL.
